(57)

CLAIM

The ornamental design for a pendant, as shown and described.

DESCRIPTION

FIG. 1 is a top perspective view of a pendant showing my design;

FIG. 2 is a bottom perspective view of the pendant;

FIG. 3 is a front elevation view of the pendant, the reverse side being a mirror image thereof;

FIG. 4 is a top edge on view of the pendant of FIG. 3, the bottom edge on view being a mirror image thereof; and,

FIG. 5 is a right side edge on view of the pendant of FIG. 3, the left side edge on view being a mirror image thereof.

1 Claim, 3 Drawing Sheets
